UNITED STATES PATENT OFFICE

CHALMERS R. REDDEN, OF FRAMINGHAM, MASSACHUSETTS

CLAW HAMMER

Application filed April 15, 1931, Serial No. 530,382. Renewed December 15, 1932.

The present invention relates to claw hammer and has for its prime object to provide an improved structure for gaining greater leverage and therefore ease of operation in the use of the claw in pulling nails and the like.

Another very important object of the invention resides in the provision of a hammer structure of this nature which is exceedingly simple, inexpensive to manufacture, strong and durable, very efficient and reliable in use and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of a hammer embodying the features of my invention.

Figure 2 is a bottom plan view thereof.

Figure 3 is a side elevation thereof showing the use of the claw structure.

Figure 4 is a longitudinal section thereof, and

Figure 5 is a transverse section taken substantially on the line 5-5 of Figure 1.

Referring to the drawings in detail it will be seen that the numeral 5 denotes a body from which extends a split socket 6 having ears 7 extending therefrom so that a handle 8 extending into the socket may be clamped in place by a bolt 9 extending through the ears 7. The portion of the body 5 adjacent the socket 6 is formed with a recess 10 opening at the bottom. A claw 11 is formed on the upper portion of the body 5. The front face of the body 5 inclines downwardly and toward the socket end thereof as is indicated at 12. The body is slightly reduced in width in comparison with the socket. Numeral 14 denotes a hammer ball or head on the upper end of which are formed a front wall 15 and side walls 16 extending rearwardly therefrom and at right angles thereto terminating in ears 17 through which extends a

bolt 18. The bolt 18 also extends through the body 5 and across the recess 10 and a spring 19 is coiled about this bolt and has one end anchored in the ball or head 14 to normally hold the same at substantially a right angle to the axis of the socket 6 and the handle 8.

The utility of the hammer is self apparent from a mere inspection of Figure 3 as it will be seen that the body may be pivoted between the ears 17 on the bolt 18 for pulling the nail the major portion of its distance and then the end of the nail may be pulled out with the ball as a fulcrum. Thus at the beginning of the pulling of a nail a greater leverage is provided as is desirable. As soon as the hammer is lifted from a position shown in Figure 3 it will be seen that the spring 19 immediately rights the ball.

It is thought that the construction, operation, utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In a hammer of the class described, a body with a claw thereon, a ball pivotally mounted on the body, and means normally holding the ball in predetermined position with respect to the body, said means being in the form of a spring mounted on the pivot and engaged with the ball.

2. A hammer of the class described including a body with a recess therein and a claw extending therefrom, a ball having a pair of walls rising therefrom and formed with ears, a bolt extending through the ears

and through the body so that the ball may pivot on the body, said bolt extending through the recess, and a spring on the bolt, said spring having an end anchored in the ball.

3. A hammer of the class described including a body with a recess therein and a claw extending therefrom, a ball having a pair of walls rising therefrom and formed

with ears, a bolt extending through the ears and through the body so that the ball may pivot on the body said bolt extending through the recess, and a spring on the bolt said spring having an end anchored in the ball, and said body having a split pocket extending in communication with the recess.
